(57) **CLAIM**

The ornamental design for a folding LED light table mirror, as shown and described.

DESCRIPTION

FIG. 1 is a front, right side and top perspective view of a folding LED light table mirror showing my new design; FIG. 2 is a rear, left side and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and, FIG. 9 is a front, right side and top perspective view of the folding LED light table mirror shown in an alternate configuration of use with two covers totally unfolded thereof. The broken lines depict portions of the folding LED light table mirror that form no part of the claimed design.

1 Claim, 9 Drawing Sheets
